[57] CLAIM

The ornamental design for a combined mounting canopy, motor and switch housing and blade irons unit for a ceiling fan, as shown and described.

DESCRIPTION

FIG. 1 is a perspective view of a combined mounting canopy motor and switch housing and blade irons unit for a ceiling fan showing my new design, the broken lines showing fan blades being for illustrative purposes only and forming no part of the claimed design; FIG. 2 is a side elevational view thereof, the opposite and adjacent sides being mirror images of that shown; FIG. 3 is a top plan view thereof; and, FIG. 4 is a bottom plan view thereof.

FIG. I

FIG. 2

FIG. 3

FIG. 4
